UNITED STATES PATENT OFFICE.

OLAF ROED, OF MINNEAPOLIS, MINNESOTA, ASSIGNOR TO J. G. MACCUNE, OF MINNEAPOLIS, MINNESOTA.

KITCHEN-REMINDER.

No. 914,364.

Specification of Letters Patent.

Patented March 2, 1909.

Application filed March 23, 1908. Serial No. 422,646.

To all whom it may concern:

Be it known that I, OLAF ROED, of Minneapolis, Hennepin county, Minnesota, have invented certain new and useful Improvements in Kitchen-Reminders, of which the following is a specification.

The object of this invention is to provide a device adapted to be hung upon the wall, and by means of which the person in charge 10 of purchasing supplies for the household can determine at a glance whether certain articles should be ordered or not, devices being provided, capable of adjustment to indicate when the different supplies are 15 exhausted.

The invention consists generally in various constructions and combinations, all as hereinafter described and particularly pointed out in the claims.

20 In the accompanying drawings, forming part of this specification, Figure 1 is front view of a kitchen reminder embodying my invention. Fig. 2 is a detail view of the same. Fig. 3 is a sectional view illustrating 25 the manner of mounting the indicators in the reminder.

In the drawing, 2 represents the plate bearing the indicating devices, having a hole 3 at its upper end to adapt the device 30 for hanging on the wall. The plate is preferably composed of a double thickness of cardboard, as indicated in Fig. 3, the sheets being secured together by any suitable means and provided with holes 4 in 35 which balls 5, such as beads or marbles are suspended on wires 6 that are embedded between the sheets composing the plate, and form the axes on which the balls rotate. These balls have their surfaces provided 40 with differently colored areas, one side of a ball being light, for instance, and the other red, so that when the ball is turned with the red or colored side visible the person in charge of purchasing supplies will be 45 minded that the article in the blank space 7 opposite the colored ball, is exhausted and that a fresh supply should be ordered. Each ball is operable independently of all the others and as many of them may be mounted 50 on the card as desired.

I have shown four columns for the supplies and the different articles may be grouped

therein or alphabetically arranged, if preferred. When an article has been ordered 55 the ball opposite the name of the article will be revolved until its light or uncolored surface is visible. Thereupon it will be understood that there is a full supply of the article on hand.

The card may be suitably ornamented 60 by a drawing or lithograph, and in the central portion thereof a thermometer and a surface for scratching matches may be provided.

As indicated in Fig. 3 the balls project 65 through the front and back of the card and are visible on both sides, my purpose being to utilize the back of the card as well as the front for a list of household articles. In using the card directions will be given to 70 revolve the balls so that two colors will be visible from the front and then it will be understood that an article listed on the back of the card is needed.

In addition to the list of articles on the 75 back of the card I may provide fortune telling paragraphs, suitable reference being made thereto by numbers or marks on the front of the card.

I claim as my invention:

80 1. A kitchen reminder comprising a card bearing the names of articles of household use, and a series of balls mounted to revolve in said card, each ball having its surface provided with differently colored areas, one 85 color indicating a supply of the article on hand and the other that the supply is exhausted.

2. A kitchen reminder comprising a card 90 having spaces thereon for the names of articles of household use, said card being composed of front and back sheets and wires embedded therein, and said card having a series of holes intersected by said wires, and beads mounted on said wires in said holes and capable 95 of revolution therein independently of one another and said beads having surfaces with differently colored areas thereon, for the purpose specified.

3. A kitchen reminder comprising a card 100 bearing the names of articles of household use and a series of balls mounted in said card opposite the names of said articles respectively, said balls projecting through holes in

said card and having a rotary movement only therein and having surfaces with differently colored areas.

4. A kitchen reminder, comprising a card having spaces thereon for the names of articles of household use, said card having a series of holes therein, and wires intersecting said holes, balls mounted on said wires in said holes, and capable of revolution therein

independently of one another and said balls having surfaces with differently colored areas thereon for the purpose specified.

In witness whereof I have hereunto set my hand this 14th day of March 1908.

OLAF ROED.
